UNITED STATES PATENT OFFICE.

ROY S. LATIMER, OF TROY, NEW YORK.

NECKBAND.

1,284,719.

Specification of Letters Patent. Patented Nov. 12, 1918.

Application filed January 17, 1918. Serial No. 212,163.

To all whom it may concern:

Be it known that I, ROY S. LATIMER, a citizen of the United States, residing at Troy, county of Rensselaer, and State of New York, have invented certain new and useful Improvements in Neckbands, of which the following is a specification.

Reference may be had to the accompanying drawings, and the reference characters 10 marked thereon, which form a part of this specification. Similar characters refer to similar parts in the several figures therein.

This invention relates to the manufacture 15 of neckbands and similar articles made of a plurality of plies of textile fabric or the like.

The principal objects of the invention are to economize in the amount of material required for the manufacture of the band, and 20 to produce a less bulky product.

Other objects will appear in connection with the following description.

Figure 1 of the drawings is a plan view 25 of a flat strip adapted to form one of the component members of the band.

Fig. 2 is a cross-section of the same taken on the broken line 2—2 in Fig. 1.

Fig. 3 is a plan view of a folded strip, 30 adapted to form another component member of the band.

Fig. 4 is a cross-section of the same taken on the broken line 4—4 in Fig. 3.

Fig. 5 is a plan view showing said folded strip superimposed upon said flat strip, as 35 in the manufacture of a band in accordance with my improved method.

Fig. 6 is a vertical cross-section of the same taken on the broken line 6—6 in Fig. 5.

Fig. 7 is a plan view of the strip shown 40 in Fig. 5, after the edge-portions of said strips have been inturned over upon the flat strip.

Fig. 8 is a cross-section of the same taken on the broken line 8—8 in Fig. 7.

Fig. 9 is a plan view of the strips with 45 the edges inturned and the flat strip folded along its longitudinal middle.

Fig. 10 is a cross-section of the same taken on the broken line 10—10 in Fig. 9.

Fig. 11 is a plan view of the finished 50 band. Fig. 12 is a cross-section of the same taken on the broken line 12—12 in Fig. 11.

Fig. 13 is a longitudinal section of the

same taken on the broken line 13—13 in Fig. 11.

Fig. 14 is a plan view of a flat strip 55 similar to that shown in Fig. 1, with a shorter folded strip superimposed thereupon as in the manufacture of a modified form of pocket-neckband in accordance with my invention.

Fig. 15 is a cross-section of the same taken on the broken line, 15—15 in Fig. 14.

Fig. 16 is a similar view showing a folded strip similar to that shown in Fig. 3 superimposed upon said shorter folded strip and said flat strip shown in Fig. 14.

Fig. 17 is a cross section of the same taken on the broken line 17—17 in Fig. 16.

Fig. 18 is a cross-section similar to Fig. 12, taken through the back buttonhole of a pocket-neckband made in the manner illustrated in Figs. 14 to 17.

In making a neckband or the like in accordance with my invention, I longitudinally 75 fold a strip to form fold-members 2, 2^a, of unequal depth whereby the fold-member, 2, is formed with an edge-portion, 2^b, projecting beyond the free edge-portion of the fold-member, 2^a.

I then superimpose said folded strip upon a flat strip, 1, with the fold-member, 2^a, next to the flat strip and with the free edge of the inner fold-member, 2^a, of said folded strip coincident with edge-portions of the 85 flat strip, and the outer fold-member, 2, of said folded strip projecting beyond said coincident edges of its inner member and the flat strip, as shown in Fig. 6.

After the folded strip, 2, 2^a, has thus been 90 superimposed upon the flat strip, said longitudinal projecting edge-portions, 2^b, of said folded strip and end edge-portions of the outer member, 2, thereof on one side of a line extending longitudinally of said flat 95 strip are inturned over upon said flat strip symmetrically with edge-portions of said flat strip on the opposite side of said longitudinal line.

Said inturning operation can be advantageously performed by the use of turning or folding machines, as is well understood in the art of making collars, cuffs and the like.

The flat strip, 1, is then folded along said 100 longitudinal line with the result that as the

edges of the strips have been inturned symmetrically upon opposite sides of said line, the inturned edge-portions of the outer fold-member, 2, of the strip, 2, 2^a, will coincide with the inturned edge-portions of the strip, 1, on the opposite side of said fold-line. The strip, 1, is thus folded longitudinally so as to bring all said inturned edge-portions between its fold-members as shown in Fig. 10.

10 The free edge of the fold-member, 2^a, and the coincident edge of the strip, 1, are thus located substantially at and within the fold formed by inturning the projecting edge, 2^b, of the outer fold-member, 2, as shown in 15 Figs. 8, 10, and 12, whereby said coincident edges are covered by said fold and prevented from raveling.

20 The band is finished by securing all of said inturned edge-portions and all of the fold-members together by a line of stitching, 4, as shown in Figs. 11 and 12, and by providing the band with buttonholes, 5 and 6, if desired, which buttonholes may extend through all or any desired number of the 25 plies of the band thus formed.

25 The band thus formed presents finished folded edges on all sides with an opening between the folded edges of its members along one side adapted for the insertion of 30 the neck or sleeve portion of a shirt or the like, not shown.

35 By terminating the free edge of the fold-member, 2^a, and the coincident edge of the strip, 1, substantially at the fold formed by inturning the projecting edge-portion, 2^b, of the fold-member, 2, I am able to make a substantial saving in the amount of material for making a band of given dimensions, and I am also able to make the band thinner 40 and less bulky along its upper edge than would be the case if either the fold-member, 2^a, or the strip, 1, or both were extended to coincide with the projecting edge, 2^b, and inturned therewith.

45 This feature of terminating the free edge of the fold-member, 2^a, and the coincident edge of the strip, 1, substantially at the fold formed by inturning the projecting edge-portion, 2^b, of the fold-member, 2, may be 50 extended throughout the ends as well as the upper edge of the band if desired, but as the proportion of material thus saved is small with respect to the length of the band as compared with the saving with respect 55 to the width of the band, it may not be deemed desirable to extend this feature to the ends of the band. Thus in Fig. 13, I have shown the end-edges of all the band members inturned.

60 In some forms of pocket-neckbands wherein the opening in the pocket is formed by leaving free from the body of the garment opposite the buttonhole, the edge-portion of the plies in which the buttonhole is 65 formed, it is desirable to insert a shorter

strip in the band opposite the said buttonholed portion, between which shorter strip and the plies through which the buttonhole does not pass, the body portion of the garment is stitched at this point.

70

In making such a pocket-neckband in accordance with my invention, I first superimpose upon the flat strip, 1, a shorter folded strip, 7, 7^a, folded to form a longitudinal folded edge, 8, the edge-portions of said shorter folded strip along the side opposite said folded edge coinciding with corresponding edge-portions of the flat strip, 1, as shown in Figs. 14 and 15.

75 The folded strip, 2, 2^a, is then superimposed upon said shorter strip, 7, and the flat strip, 1, as shown in Figs. 16 and 17, and in the same manner with respect to the strip, 1, as above described, after which the edges of the strips are inturned and the flat strip, 1, is folded longitudinally and the band finished, all as previously described, a cross-section of the resultant band being shown in Fig. 18.

80 The shorter strip, 7, is preferably folded along its longitudinal middle, making its fold-members, 7 and 7^a, of equal depth; but for certain purposes of the invention they may be made of different depths if desired.

85 A buttonhole may be formed in such a pocket-neckband through the fold-members, 1^a and 1^b, of the flat strip, 1, or through the fold-members, 2, 2^a, as may be desired, said shorter strip, 7, 7^a, taking the place of the buttonholed members in securing the neckband to the body of the garment opposite such buttonhole portion of the band.

90 For convenience in preserving the proper relative positions of the strips in the manufacture of the band, they may be temporarily pasted together as is well understood in the art of making collars, etc.

95 I have used the word "superimposed" with respect to the blanks as they are shown in the drawings; but it will of course be understood that for convenience in performing the inturning and folding operations, the assembled blanks may be inverted from the positions shown in the drawings.

100 What I claim as new and desire to secure by Letters Patent is—

110 1. A band comprising two longitudinally folded strips superimposed one upon the other with the edge-portions of the outer fold-members only of both strips along the ends and the side opposite the fold inturned and stitched between the fold-members of one of said strips, the inner fold-member of one of said strips terminating substantially at and stitched within the fold formed by inturning said edge-portions of said other strip.

115 2. A band comprising two longitudinally folded strips superimposed one upon the other with the edge-portions of the outer

120

125

130

fold-members only of both strips along the ends and the side opposite the fold inturned and stitched between the fold-members of one of said strips, the inner fold-member of 5 both of said strips terminating substantially at and stitched within the fold formed by inturning said edge-portions of said other strip.

3. A band comprising two longitudinally 10 folded strips superimposed one upon the other with the edge-portions of the outer fold-members only of both strips along the ends and the side opposite the fold inturned and stitched between the fold-members of 15 one of said strips, the inner fold-member of one of said strips terminating substantially at and stitched within the fold formed by inturning said edge-portions of said other strip; and a shorter strip interposed between 20 said other strips, said shorter strip having a longitudinal folded edge and its edge-portion along the side opposite said folded edge stitched within said fold in said second-mentioned strip.

25 4. That improvement in the art of making bands which consists in superimposing a longitudinally folded strip upon a flat strip with the outer fold-member of the folded strip projecting beyond the longitudinal 30 edge of another member of said strips; inturning over upon said flat strip said projecting edge-portions of said folded strip, and end edge-portions of the outer member thereof on one side of a line extending longitudinally of said flat strip, symmetrically with edge-portions of said flat strip on the opposite side of said longitudinal line; folding said flat strip along said longitudinal line, causing inturned edge-portions of the 35 outer fold-member of said first mentioned strip to coincide with inturned edge-portions of said second-mentioned strip on the opposite side of said longitudinal line with all said inturned edge-portions between the 40 fold-members of said second-mentioned strip, and said other member of said strips terminating substantially at and within the fold formed by inturning said projecting edge of the outer fold-member of said first- 45 mentioned strip; and stitching all of said inturned edges and all of said fold-members together.

50 5. That improvement in the art of making bands which consists in superimposing a longitudinally folded strip upon a flat strip with the free edge of the inner fold-member of said folded strip coincident with

the edge of said flat strip and the outer fold-member of said folded strip projecting beyond said edges; inturning over upon said 55 flat strip said projecting edge-portions of said folded strip, and end edge-portions of the outer member thereof on one side of a line extending longitudinally of said flat strip, symmetrically with edge-portions of 60 said flat strip on the opposite side of said longitudinal line; folding said flat strip along said longitudinal line, causing inturned edge-portions of the outer fold-member of said first-mentioned strip to coincide with inturned edge-portions of said second-mentioned strip on the opposite side of said 65 longitudinal line, with all said inturned edge-portions between the fold-members of said second-mentioned strip, and the coincident edge-portions of said inner fold-member and said flat strip substantially at and within the fold formed by inturning said 70 projecting edge of the outer fold-member of said first-mentioned strip; and stitching all of said inturned edges and all of said fold-members together.

6. That improvement in the art of making bands which consists in superimposing a longitudinally folded strip upon a longer flat 85 strip; superimposing upon said folded strip and said flat strip a longer folded strip with the outer fold-member of the latter projecting beyond the longitudinal edge of other members of said strips; inturning over 90 upon said flat strip said projecting edge-portions of said longer folded strip, and end edge-portions of the outer member thereof on one side of a line extending longitudinally of said flat strip, symmetrically with 95 edge-portions of said flat strip on the opposite side of said longitudinal line; folding said flat strip along said longitudinal line, causing inturned edge-portions of the outer fold-member of said longer folded strip to coincide with inturned edge-portions of said second-mentioned strip on the opposite side of said longitudinal line, with all said inturned edge-portions between the fold-members of 100 said second-mentioned strip, and other members of said strips terminating substantially at and within the fold formed by inturning said projecting edge of the outer fold-member of said longer folded strip; and stitching all of said inturned edge-portions and 105 all of said fold-members together.

In testimony whereof I have hereunto set my hand this 8th day of January, 1918.

ROY S. LATIMER.
